UNITED STATES PATENT OFFICE

147,804

DESIGN FOR A CLOTHESPIN

Mario Maccaferri, Rye, N. Y.

Application May 26, 1947, Serial No. 139,279

Term of patent 14 years

(Cl. D17—6)

To all whom it may concern:

Be it known that I, Mario Maccaferri, a citizen of the United States of America, residing at Rye, New York, in the county of Westchester and State of New York, have invented a new, original, and ornamental Design for Clothespin, of which the following is a specification, reference being had to the accompanying drawing, forming part thereof.

Fig. 1 is a side perspective view of a clothespin showing my new design;

Fig. 2 is a side view; and

Fig. 3 is an edge elevational view.

I claim:

The ornamental design for a clothespin, substantially as shown.

MARIO MACCAFERRI.
